HYDRAULIC TRANSMISSION

Ralph E. Flanders, Springfield, Vt., assignor to
 Jones & Lamson Machine Company, Springfield,
 Vt., a corporation of Vermont

Application January 7, 1932, Serial No. 585,221

16 Claims. (Cl. 60—52)

This invention relates to systems for the transmission and control of power, such a system including a motor actuated by liquid under pressure and means for delivering liquid under pressure under controlled conditions to and discharging it from the motor. In such systems it is found desirable to provide a neutral position of the control mechanism in which the motor may, if desired, be moved by hand, or otherwise independently of the liquid. One method of doing this is to connect both sides of the motor with each other which may be done by connecting both to discharge. It is then possible to move the motor as desired, the liquid flowing from one side to the other of the motor, depending on the direction of motor movement. The liquid in the motor and its intermediate pipes is under relatively low pressure under such conditions. If the control valve be moved from this neutral position quickly to one in which liquid under high pressure is admitted to one side of the motor while the rate of discharge is limited in order to control the motor speed, there is a tendency for the motor and the parts moved thereby to jump ahead suddenly due to the compressibility of the low pressure liquid on the discharge side of the motor, in the motor and its pipe connections to the discharge rate control mechanism.

One of the objects of the present invention is to prevent this action, and it is done according to this invention, by opening both sides of the motor to high pressure liquid when the valve is moved from its neutral position to either operative position and before it applies the high pressure to one side only of the motor and permits discharge from the opposite side.

While in its broader aspects the invention is not limited to any particular embodiment of such a hydraulic transmission system, its application to a system embodying a liquid meter in the discharge of the motor for regulating its speed and particularly as applied to the actuation of a traversing carriage of a machine tool will be more completely described.

Referring to the accompanying drawings,

Figure 1 is a fragmentary view partly in front elevation and partly broken away and in section of a lathe embodying this invention.

Figure 2 is an end elevation of the meter and valve mechanism.

Figure 3 is a view showing the mechanism in top plan, a portion of the machine frame being shown in horizontal section.

Figures 4 to 8 inclusive are detail sections on correspondingly numbered section lines of Figure 3.

Figure 9 is a diagrammatic longitudinal section to a larger scale through the meter and valve mechanisms, the latter being in neutral position.

Figures 10 and 11 are views similar to portions of Figure 9, but showing the valves in intermediate and low speed positions, respectively, for actuation of the carriage to the left.

Figure 12 is a view similar to Figure 11, but showing the parts in position for low speed carriage movement to the right.

Figure 13 is a detail section on line 13—13 of Figure 9.

Figure 14 is a side elevation partly broken away 10 of one of the valves.

Figure 15 is an end elevation partly broken away of the same.

Figures 16 and 17 are sections similar to portions of Figures 9 to 12 but showing the parts 15 in fast motion positions for carriage travel in opposite directions.

Figure 18 is a view similar to a portion of Figure 10 but showing an intermediate position of the valves to the right of the neutral position.

Referring first to Figure 1, at 1 is shown the cylinder of a reversible cylinder and piston hydraulic motor, the piston being shown at 2 and having a piston rod 3 which is intended to be secured to a traversing carriage (not shown) of 25 a lathe, the headstock of which is shown at 4 carrying a work engaging chuck 5. At 6 in the base of the machine is a suitable supply tank for a liquid, such as oil or the like, which may be supplied under pressure to one or the other 30 side of the motor cylinder 1, as desired, as, for example, by means of a pump of any suitable description (not shown) which may be provided with an actuated pulley 7 by which it may be driven. This may thus supply fluid under pressure to a valve mechanism indicated generally at 8 by which the control of fluid to and from the motor may be produced. At 9 is shown a liquid metering device which may be driven to regulate the rate at which fluid may be passed 35 therethrough, as by means of a belt 10, passing about an actuating pulley 11 of the metering device and a pulley 12 carried by the headstock spindle.

The metering device may be of any suitable 45 type but as herein shown in Figures 8 and 9, it comprises a cage 20 carrying in circular arrangement a series of chambers 21, each being closed off at one end by a slidable plunger 22. The outer ends of these plungers engage against the inner 50 face of a swash plate 23 which may be angularly adjusted about a fulcrum 24 as by means of a cam 25 carried by a rock shaft 26 and provided with an actuating handle 127 to determine the amplitude of motion of the plungers during 55 the rotation of the cage 20. This cage is rotatable on a valve 125 which has ports shown in Figure 7 so positioned as to admit fluid from a passage 27 to those chambers which are approaching that side of the swash plate tilted 60

away from the cage and to discharge fluid from those chambers which are being retracted as the plungers therein are moving toward the nearer side of the swash plate through the exhaust passage 28 from which it may return directly to the storage tank. In order to permit rotation of the meter cage in either direction a 180° lost motion between the valve and swash plate is provided through the stop pin 29 engageable with either of the shoulders 290 or 490 of the valve as shown in Figure 5. The cage is rotated by geared connections to a shaft 30, to the outer end of which is secured the driving pulley 11. This particular construction of meter is fully shown, described and claimed in Patent No. 1,924,738 granted to me on application Serial No. 511,806, filed January 28, 1931, for Hydraulic power transmission and metering device therefor.

to the displacement of the piston rod of the motor.

rection into the position shown in Figure 16 where the pipe 71 is connected by the right hand valve passage 65 directly with the chamber 88 and to discharge through the pipe 74. At the same time 5 the spring abutment at the left hand valve end has been compressed so as to tend to return the valve to its slow motion position.

From the foregoing description of an embodiment of this invention, it should be evident to 10 those skilled in the art that various changes and modifications might be made without departing from the spirit or scope of this invention as defined by the appended claims.

I claim:

1. In combination, a fluid pressure motor having admission and exhaust passages, a source of fluid under pressure, and a valve mechanism for controlling the supply of fluid to said motor, said mechanism including parts cooperating to close 20 off fluid from said source to said motor in one valve position, to admit fluid under pressure from said source to said motor admission passage only to drive said motor in another valve position, and in a third position to admit fluid under pressure to both admission and exhaust sides of said motor 25 while both sides of said motor are closed to discharge, said third position being intermediate to the other positions and through which said parts must pass when being moved from one to the other of said positions.

2. In combination, a fluid pressure motor having admission and exhaust passages, a source of fluid under pressure, and a valve mechanism for controlling the supply of fluid to said motor, said mechanism including parts cooperating to close off fluid from said source to said motor in one valve position and to open both motor passages to discharge, to admit fluid under pressure from said source to said motor admission only to drive 40 said motor in another valve position, and in a third position to admit fluid under pressure to both admission and exhaust sides of said motor, said third position being intermediate to the other positions and through which said parts must pass 45 when being moved from one to the other of said positions.

3. In combination, a fluid pressure motor, a source of fluid under pressure, a fluid meter, and a valve mechanism for controlling admission of fluid from said source to said motor, the discharge of fluid from said motor and the interposition of said meter in the flow of fluid through said motor or the by-passing of said meter, said valve mechanism including parts cooperating to cut off 50 said motor from said source in one valve position, to open said motor to said source and to discharge and to interpose said meter in the flow of fluid in another valve position, to open both 55 sides of said motor to fluid from said source in an intermediate position, and to open said motor to said source and discharge and to by-pass said meter in a fourth position.

4. In combination, a fluid pressure motor, a source of fluid under pressure, a fluid meter, and a valve mechanism for controlling admission of fluid from said source to said motor, the discharge of fluid from said motor and the interposition of said meter in the flow of fluid through said motor or the by-passing of said meter, said valve mechanism including parts cooperating to cut off 60 said motor from said source and to open both sides of said motor to fluid from said source in one valve position, to open one side of said motor to discharge and to by-pass said meter in a fourth position.

5. In combination, a fluid pressure motor having admission and exhaust passages, a source of fluid under pressure, a fluid meter, and a valve mechanism for controlling admission of fluid from said source to said motor, the discharge of fluid from said motor and the interposition of said meter in the flow of fluid through said motor or the by-passing of said meter, said valve mechanism including parts cooperating to cut off 10 said motor from said source in one valve position, to open both sides of said motor to fluid from said source in another position, to open said motor intake to said source and to interpose said meter in the discharge in another position, and to open said motor intake to said source and to by-pass said meter in still another position.

6. In combination, a fluid pressure motor having intake and discharge passages, a source of fluid under pressure, a fluid meter, and a valve mechanism for controlling admission of fluid from said source to said motor, the discharge of fluid from said motor and the interposition of said meter in the flow of fluid through said motor or the by-passing of said meter, said valve mechanism including parts cooperating to cut off 15 said motor from said source in one valve position, to open both sides of said motor to fluid from said source in another position, to open said motor intake to said source and to interpose said meter in the discharge in another position, and to open said motor intake to said source and to by-pass said meter in still another position.

7. In combination, a fluid pressure motor having intake and discharge passages, a source of fluid under pressure, a fluid meter, and a valve mechanism for controlling admission of fluid from said source to said motor, the discharge of fluid from said motor and the interposition of said meter in the flow of fluid through said motor or the by-passing of said meter, said valve mechanism including parts cooperating to cut off 20 said motor from said source in one valve position, to open both sides of said motor to fluid from said source in another position, to open said motor intake to said source and to interpose said meter in the discharge in another position, and to open said motor intake to said source and to by-pass said meter in still another position.

8. In combination, a fluid pressure motor having intake and discharge passages, a source of fluid under pressure, a fluid meter, and a valve mechanism for controlling admission of fluid from said source to said motor, the discharge of fluid from said motor and the interposition of said meter in the flow of fluid through said motor or the by-passing of said meter, said valve mechanism including parts cooperating to cut off 25 said motor from said source in one valve position, to open both sides of said motor to fluid from said source in another position, to open said motor intake to said source and to interpose said meter in the discharge in another position, and to open said motor intake to said source and to by-pass said meter in still another position.

9. In combination, a reversible fluid pressure motor having intake and discharge passages, a source of fluid under pressure, and a valve mechanism for controlling the supply of fluid to and discharge from said motor, said valve mechanism having an intermediate neutral position in which both passages of said motor are cut off from said source, operative positions on either side of said neutral position in which one or the other side of said motor is connected to said source and the opposite side to discharge, and positions intermediate said neutral and operative positions in each of which both sides of said motor are connected to said source.

10. In combination, a reversible fluid pressure motor having intake and discharge passages, a source of fluid under pressure, and a valve mechanism for controlling the supply of fluid to and discharge from said motor, said valve mechanism having an intermediate neutral position in which both passages of said motor are cut off from said source and open to discharge, operative positions on either side of said neutral position in which one or the other side of said motor is connected to said source and the opposite side to discharge, and positions intermediate said neutral and operative positions in each of which both sides of said motor are connected to said source.

11. In combination, a reversible fluid pressure motor having intake and discharge passages, a source of fluid under pressure, a liquid meter, and a valve mechanism for controlling the supply of fluid to and discharge from said motor and for interposing said meter in the fluid circuit,

- said valve mechanism having an intermediate neutral position in which both passages of said motor are cut off from said source, slow motion positions on either side of said neutral position 5 in which one or the other side of said motor is connected to said source and the other side to discharge through said meter, positions intermediate said neutral and slow motion positions in each of which both sides of said motor are 10 connected to said source and cut off from discharge, and fast motion positions beyond said slow motion positions in each of which one or the other side of said motor is connected to said source and the opposite side to discharge by- 15 passing said meter.
10. In combination, a reversible fluid pressure motor having intake and discharge passages, a source of fluid under pressure, a liquid meter, and a valve mechanism for controlling the supply 20 of fluid to and discharge from said motor and for interposing said meter in the fluid circuit, said valve mechanism having an intermediate neutral position in which both passages of said motor are cut off from said source, and open 25 to discharge through said meter, slow motion positions on either side of said neutral position in which one or the other side of said motor is connected to said source and the other side to discharge through said meter, positions intermediate said 30 neutral and slow motion positions in each of which both sides of said motor are connected to said source and cut off from discharge, and fast motion positions beyond said slow motion positions in each of which one or the other side of said motor is connected to said source and the opposite side to discharge by-passing said meter.
11. In combination, a fluid pressure motor having intake and discharge passages, a source of fluid under pressure, a fluid meter, and a valve mechanism for controlling admission of fluid from said source to said motor, the discharge from said motor and the interposition of said meter in the discharge from said motor, said mechanism including parts cooperating to 40 cut off said motor from said source in one valve position, to open both passages of said motor and the passages from said motor to said meter to said source in another position, to open said motor intake to said source and to interpose said meter in the discharge in another position, and to open said motor intake to said source and to by-pass said meter in still another position.
12. In combination, a fluid pressure motor having intake and discharge passages, a source of fluid under pressure, a fluid meter, and a valve mechanism for controlling admission of fluid from said source to said motor, the discharge from said motor and the interposition of said meter 45 in the discharge from said motor, said mechanism including parts cooperating to cut off said motor from said source and to open both sides of said motor to discharge in one valve position, to open both passages of said motor and the passages from said motor to said meter to said source in another position, to open said motor intake to said source and to interpose said meter in the discharge in another position, and to open said motor intake to said source and to by-pass said meter in still another position.
13. In combination, a reversible fluid pressure motor having intake and discharge passages, a

- source of fluid under pressure, a liquid meter, and a valve mechanism for controlling the supply of fluid to and discharge from said motor and for interposing said meter in the fluid circuit, said valve mechanism having an intermediate neutral position in which both passages of said motor are cut off from said source, slow motion positions on either side of said neutral position in which one or the other side of said motor is connected to said source and the other side to discharge 10 through said meter, positions intermediate said neutral and slow motion positions in each of which both sides of said motor and the passages from said motor to said meter are connected to said source and cut off from discharge, and fast 15 motion positions beyond said slow motion positions in each of which one or the other side of said motor is connected to said source and the opposite side to discharge by-passing said meter.
14. In combination, a reversible fluid pressure 20 motor having intake and discharge passages, a source of fluid under pressure, a liquid meter, and a valve mechanism for controlling the supply of fluid to and discharge from said motor and for interposing said meter in the fluid circuit, said valve mechanism having an intermediate neutral position in which both passages of said motor are cut off from said source and open to discharge through said meter, slow motion positions on either side of said neutral position in which one or the other side of said motor is connected to said source and the other side to discharge through said meter, positions intermediate said neutral and slow motion positions in each of which both sides of said motor and the passages 30 from said motor to said meter are connected to said source and cut off from discharge, and fast motion positions beyond said slow motion positions in each of which one or the other side of said motor is connected to said source and the opposite side to discharge by-passing said meter.
15. In combination, a reversible fluid pressure motor having intake and discharge passages, a source of fluid under pressure, and a valve mechanism for controlling the supply of fluid to and discharge from said motor, said valve mechanism having an intermediate neutral position in which both passages of said motor are cut off from said source, operative positions on either side of said neutral position in which one or the other side of said motor is connected to said source and the opposite side to discharge, and positions intermediate said neutral and operative 40 positions in each of which both sides of said motor are connected to said source and closed from said discharge.
16. In combination, a reversible fluid pressure motor having intake and discharge passages, a source of fluid under pressure, and a valve mechanism for controlling the supply of fluid to and discharge from said motor, said valve mechanism having an intermediate neutral position in which both passages of said motor are cut off from said source and open to discharge, operative positions on either side of said neutral position 45 in which one or the other side of said motor is connected to said source and the opposite side to discharge, and positions intermediate said neutral and operative positions in each of which both sides of said motor are connected to said source and closed from said discharge.

RALPH E. FLANDERS.
